FLUID FUEL BURNER CONTROL

John P. Kriechbaum, Minneapolis, Minn., assignor to Minneapolis-Honeywell Regulator Company, Minneapolis, Minn., a corporation of Delaware

Application January 23, 1936, Serial No. 60,481

8 Claims. (Cl. 158—28)

My invention relates to a fluid fuel burner control and more particularly to a control for a gas burner employing the pilot burner to ignite the same, which pilot burner is lighted only 5 when the burner is to be put into operation and during such operation.

In certain types of gas burner control systems it is the practice to provide means for igniting the pilot burner each time that it is desired to 10 place the main burner into operation. In such systems, a valve is usually provided for controlling the supply of gas to the pilot burner and some means is provided for igniting the gas supply to the pilot burner. In addition, it is 15 customary as a safety measure to provide a thermostatic device responsive to the presence of a flame at the pilot burner, commonly known as a "safety pilot thermostat". This device is employed to prevent the main gas valve being 20 opened until the pilot burner has been lighted. Arrangements have also been provided, which utilize the safety pilot thermostat to place the ignition means out of operation after the pilot has been lighted.

25 The prior systems of this type have all had certain definite disadvantages. In one such system the main valve is controlled only by the safety pilot thermostat and is not under the control of the room thermostat. If for any reason, 30 the pilot valve is stuck in an open position, there is a possibility in this system of a dangerous condition being created by reason of the continued operation of the main burner after the thermostat ceases to call for heat. Another type 35 of system overcomes the disadvantage just mentioned by employing a relay which adds to the expense and complication of the system.

An object of the present invention is to provide a system of a similar type just discussed 40 wherein the main valve is under control of both the thermostat and the safety pilot and wherein the use of a relay is eliminated by the utilization of a switch operated by the operating means for the pilot valve.

45 A further object of this invention is to provide a control system employing a plurality of valves in which a switch actuated in connection with the opening of one of the valves controls, in conjunction with a thermostatic switch, the 50 action of the other valve.

A further object of the present invention is to provide a burner control system in which the circuit to the ignition means for the burner is controlled by a switch which is closed upon opening 55 movement of the burner valve.

Other objects of the invention will be apparent upon a consideration of the accompanying specification, claims, and drawing.

In the single figure of the drawing, I have shown a preferred form of my invention in a more or less schematic manner. Referring to said figure, a main gas burner is designated by the numeral 10 and a pilot burner by the numeral 11. The main burner is connected through a pipe 12 and a main valve 13 with a gas supply pipe 14. Connected to the gas supply pipe on the inlet side of valve 13 is a pipe 15 which supplies fuel to the pilot burner 11 under control of a pilot valve 16.

Located in proximity to the pilot burner 11 is a safety pilot thermostat 18. This safety pilot thermostat may be of any conventional form wherein switch means are provided so that when the pilot is cold one set of contacts are in engagement and when the pilot is hot another set is engaged. In the schematic showing of the safety pilot thermostat in the drawing, the temperature sensitive element which is shown as a bimetallic element is indicated by reference number 19. This bimetallic element is adapted to be 25 engaged with either of two contacts, 20 and 21. When the pilot burner is not lighted and the safety pilot thermostat is cold, as indicated in the drawing, the bimetallic element 19 is in engagement with the contact 20, which contact 30 may be referred to as the "cold contact". When the pilot burner is lighted, the bimetallic element is deflected to the left so as to be in engagement with the contact 21, which contact 35 may be referred to as the "hot contact".

Located in proximity to the pilot burner 11 are two electrodes 24 which are spaced apart to provide a spark gap therebetween. These electrodes are connected to the opposite terminals of a secondary 25 of a step-up spark transformer 26. The transformer 26 has in addition to the high voltage secondary 25, a low voltage primary 27.

A step-down transformer 29 supplies power for the operation of my system. This transformer 45 comprises a line voltage primary 30 and a low voltage secondary 31. The primary 30 is connected to line wires 32 and 33.

The thermostat controlling the operation of my system is designated by the reference numeral 34. This thermostat may take any conventional form and may be responsive to any controlling condition. In the present case, the thermostat is intended to be a room thermostat which comprises a bimetallic element 35 to which 50

is attached a contact arm 36 adapted to be moved into engagement with contacts 37 and 38. It will be noted that the contact arm 36 is less widely spaced from contact 37 than from contact 38. Thus upon movement of the contact arm 36 in the direction of contacts 37 and 38, the contact arm is first moved into engagement with contact 37 and after a predetermined temperature change into engagement also with contact 38. As indicated by a legend on the drawing, a bimetallic element 35 is so arranged that contact arm 36 is moved in the direction of contacts 37 and 38 upon a decrease in the temperature.

15 The main gas valve 13 may be of any type employing electrically actuated means for opening the valve. For purposes of illustration, I have shown an actuating means of the "stalled motor" type, wherein the valve is opened by a motor 20 against the action of a spring which tends to move a valve to a closed position and which, upon deenergization of the motor, so moves the valve. The motor of this actuating means is designated by the reference numeral 40 and comprises a 25 rotor 41 and field winding 42. The rotor 41 is connected through a suitable reduction gearing 43 with a gear 44. Secured to this gear 44 is a pin 45, which pin is adapted to engage with the curved portion of a hook 47. The hook 47 is 30 pivotally connected to a lever 48, which in turn, is connected to a valve stem 49 of the valve 13. A valve stem 49 is connected to a valve disk 50 which is biased to a closed position by a spring 51. Upon energization of the motor, the gear 44 35 is rotated in the direction of the arrow shown thereon causing the pin 45 to engage the hook 47 and to raise the lever 48 and accordingly the valve 50. A pin 52 is secured to any suitable support and limits the upward movement of lever 48 and 40 consequently of the valve 50. Upon deenergization of the motor, the spring is effective to move the valve downwardly, moving therewith the gear train 43 and the motor 40 and returning them to the position shown in the drawing.

45 Although the pilot valve may be in the form of any power actuated valve with provision for a switch actuated upon the energization of the valve actuating means, I have shown for purposes of illustration, a solenoid valve having a 50 switch which is moved to closed position upon energization of the solenoid. This valve may conveniently be of the form of the valve disclosed in the co-pending application of Willis H. Gille, Serial Number 39,701, filed September 9, 1935.

55 I have shown this valve schematically as comprising a valve body 54 on which is mounted a solenoid coil 55, with which is associated a core 56 of magnetic material. The core is attached to a valve disk 57 so that upon energization of the 60 solenoid coil 55 with the resulting upward movement of the core 56, the valve disk 57 is moved into open position. Also associated with the solenoid 55 is a switch comprising a switch blade 58 to which is secured an armature member 59.

65 Upon energization of the solenoid, the armature member 59 and accordingly the switch blade 58 is moved downwardly to cause engagement of the switch blade with a stationary contact 60.

The various members are shown in the drawing 70 in the position they assume when the temperature in the space to be heated is at or above the desired value. Upon the temperature dropping below this value, the contact arm 36 is moved in the direction of contacts 37 and 38. The contact 75 arm 36 will first engage contact 37 but this en-

gagement will not cause the establishment of any energizing circuit. If the temperature continues to drop, however, the contact arm 36 will be moved into engagement with both contacts 37 and 38, causing the following energizing circuit 5 to be established: from the right hand terminal of secondary 31 through conductors 62 and 63, contact 38, contact arm 36, contact 37, conductor 64, solenoid winding 55 and conductors 65, 66 and 67 to the left hand terminal of secondary 31. 10 This causes the energization of solenoid winding 55 with the result that switch blade 58 is moved into engagement with contact 60 and the valve 16 is opened to admit gas to the pilot. At the same time the following circuit is established 15 through the primary 27 of the spark transformer 26: from the right hand terminal of secondary 31, through conductors 62 and 63, contact 38, contact arm 36, bimetallic element 35, conductor 68, conductor 69, bimetallic element 19, contact 20, 20 conductor 10, primary 27, and conductors 71, 66, and 67 to the left hand terminal of secondary 31.

The moving of switch blade 58 into engagement with contact 60 as the result of energization of solenoid winding 55 causes the following holding 25 circuit to be established to the solenoid winding: from the right hand terminal of secondary 31 through conductors 62 and 72, contact 60, switch blade 58, conductors 73 and 68, bimetallic element 35, contact arm 36, contact 37, conductor 64, solenoid winding 55, and conductors 65, 66 and 67 to the left hand terminal of secondary 31. At the same time, a holding circuit is established through the primary of spark transformer 27 as follows: from the right hand terminal of secondary 31, through conductors 62 and 72, contact 60, switch blade 58, conductors 73 and 69, bimetallic element 19, contact 20, conductor 10, primary 27, and conductors 71, 66 and 67 to the left hand terminal of secondary 31. The result 35 of the establishment of these two holding circuits is that the solenoid valve will remain open and the spark transformer will remain energized even though contact arm 36 should move away from contact 38 as might occur because of some slight 40 vibration or very slight temperature fluctuation. In this manner sudden starting and stopping of the apparatus is avoided.

The result of the opening of the pilot valve 16 and the energization of the spark transformer 26 50 is that the two conditions necessary for ignition of the pilot burner have been established. If the apparatus is functioning properly, the gas supply to the pilot burner 11 by reason of the valve 16 being open will be ignited by a spark appearing 55 across the electrodes 24 by reason of the energization of the spark transformer 26. After the pilot burner is lighted, the bimetallic element 19 of the safety pilot thermostat 18 will soon become heated with the result that the element 19 60 is moved out of engagement with the cold contact 20 and into engagement with the hot contact 21. The moving of the bimetallic element 19 out of engagement with contact 20 results in the circuit through primary 27 and the ignition transformer 65 being broken. This causes the deenergization of the ignition transformer, the operation of which is no longer needed by reason of the pilot burner being lighted.

The moving of the bimetallic element 19 into 70 engagement with the hot contact 21 results in the following circuit being established through field winding 42 of the motor 40 which actuates the main gas valve: from the right hand terminal of secondary 31 through conductors 62 and 75

72, contact 60, switch blade 58, conductors 73 and 69, bimetallic element 19, contact 21, conductor 75, motor field winding 42, and conductor 67 to the left hand terminal of secondary 31. This 5 results in the energization of the motor 40 causing the same to rotate the gear 44 in the direction of the arrow thereon and hence causing the opening of the main gas valve 13 as previously explained. The opening of the main gas valve 10 permits gas to flow to the main burner 10 where it is ignited by the pilot burner. The main burner will then continue in operation until the temperature in the room or in the space to be heated has risen sufficiently that contact arm 36 is separated from contact 37 causing the deenergization 15 of the entire system and restoring the parts to the positions shown in the drawing.

It will be noted that the field winding 42 of the motor operating the main gas valve is under 20 control of both the safety pilot thermostat and the room thermostat. The control of the main gas valve motor by the thermostat is effected through switch 58 and contact 60 which remain closed only so long as the thermostat is calling 25 for heat. The moment that the contact arm 36 separates from contact 37, the solenoid winding 55 is deenergized permitting separation of switch blade 58 from contact 60 thus interrupting the circuit to the field winding 32. It will further 30 be noted that this control of the main gas valve in addition to that by the safety pilot thermostat is effected without the use of an additional relay. It will further be noted that the switch blade 58 and contact 60 function both to control 35 a holding circuit for the solenoid and ignition means and also to control the main valve motor. In this manner, I have obtained a relatively simple and inexpensive control system in which a minimum of parts are employed but in 40 which absolute safety in the event of any contingencies is assured.

While I have shown a specific embodiment of my invention, it is to be understood that this is for purposes of illustration only and that my invention is to be limited only by the scope of the 45 appended claims.

I claim as my invention:

1. In a fluid fuel burner control system, a pilot burner, a main burner, a pilot burner valve, a 50 main burner valve, an electric motor for operating each of said valves, a switch associated with the pilot valve motor, said motor being operative upon energization thereof to open said pilot valve and close said switch, a switch responsive to a 55 controlling condition, electrically operated ignition means for said pilot burner, a source of electrical energy, circuit means effective upon closure of said condition responsive switch to simultaneously connect said pilot valve motor and said 60 ignition means with said source of energy, and circuit means including and controlled by said switch associated with said pilot valve motor for connecting said main valve motor with said source of energy.

65 2. In combination, a plurality of valves, an electric motor for each of said valves, a switch associated with one of said motors, said motor being operative when energized to move its associated valve from a first to a second controlling position and to simultaneously close said switch, a switch responsive to a condition and having a pair of contacts which at a predetermined value of said condition are moved into unstable engagement with each other, a source of 70 energy, circuit means controlled by said pair of 75

contacts of said condition responsive switch for connecting said motor associated with said switch with said source of energy, holding circuit means for said motor independent of said pair of contacts and controlled by said first named switch, 5 and energizing circuit means for the other of said motors including and controlled by said first named switch.

3. In combination, a plurality of valves, an electric motor for each of said valves, a switch 10 associated with one of said motors, said motor being operative when energized to move its associated valve from a first to a second controlling position and to simultaneously close said switch, a switch responsive to a condition and 15 having two sequentially engageable pairs of contacts, a source of energy, circuit means controlled by both pairs of contacts of said condition responsive switch for connecting said motor associated with said switch with said source of energy, holding circuit means for said motor independent of the last to be engaged of said pairs of contacts and controlled by said first named switch, and energizing circuit means for the other of said motors including and controlled by 20 25 said first named switch.

4. In a fluid fuel burner control system, a pilot burner, a main burner, a pilot burner valve, a main burner valve, an electric motor for operating each of said valves, a switch associated with 30 the pilot valve motor, said motor being operative upon energization thereof to open said pilot valve and close said switch, a switch responsive to a controlling condition and comprising a pair of contacts which at a predetermined value of said condition are moved into unstable engagement with each other, a source of energy, circuit means controlled by said pair of contacts of said condition responsive switch for connecting said pilot valve motor with said source of energy, holding 35 circuit means for said motor independent of said pair of contacts and controlled by said first named switch, and energizing circuit means for said main valve motor including and controlled by said first named switch.

5. In a fluid fuel burner control system, a pilot burner, a main burner, a pilot burner valve, a main burner valve, an electric motor for operating each of said valves, a switch associated with the pilot valve motor, said motor being operative upon energization thereof to open said pilot valve and close said switch, a switch responsive to a controlling condition and comprising two sequentially engageable pairs of contacts, a source of energy, circuit means controlled by both pairs of contacts of said condition responsive switch for connecting said pilot valve motor with said source of energy, holding circuit means for said motor independent of the last to be engaged of said pairs of contacts and controlled by said 60 first named switch, and energizing circuit means for said main valve motor including and controlled by said first named switch.

6. In a fluid fuel burner control system, a pilot burner, a main burner, a pilot burner valve, a main burner valve, an electric motor for operating each of said valves, a switch associated with the pilot valve motor, said motor being operative upon energization thereof to open said pilot valve and close said switch, a switch responsive to a controlling condition and comprising a pair of contacts which at a predetermined value of said condition are moved into unstable engagement with each other, a source of energy, circuit means controlled by said pair of 75

contacts of said condition responsive switch for connecting said pilot valve motor with said source of energy, holding circuit means for said motor independent of said pair of contacts and controlled by said first named switch, means for igniting said pilot burner, a temperature responsive switch adjacent to said pilot burner and moved to closed position when subjected to the heat of the pilot flame, and energizing circuit means for said main valve motor including and controlled by said first named switch and by said temperature responsive switch.

7. In a temperature control system, apparatus employing a fluid, a valve controlling the flow of said fluid to said apparatus, an electrical motor for operating said valve, a switch comprising a single pair of contacts associated with said motor, said motor being operative upon energization thereof to move said valve from a first to a second controlling position and to simultaneously close the contacts of said switch, a switch responsive to the temperature of a controlling medium and having a pair of contacts which at a predetermined value of said condition are moved into unstable engagement with each other, a source of energy, circuit means controlled by said pair of contacts of said condition responsive switch for connecting said motor with said source of energy, holding circuit means for said motor independent of said pair of contacts of said condition responsive switch and including and controlled by said first named switch, further electrically operated apparatus whose operation prior to the movement of said valve to said second controlling position is not desirable, and

circuit means also including and controlled by said first named switch for energizing said further apparatus.

8. In a temperature control system, apparatus employing a fluid, a valve controlling the flow of said fluid to said apparatus, an electrical motor for operating said valve, a switch comprising a single pair of contacts associated with said motor, said motor being operative upon energization thereof to move said valve from a first to a second controlling position and to simultaneously close the contacts of said switch, a switch responsive to the temperature of a controlling medium and having a pair of contacts which at a predetermined value of said condition are moved into unstable engagement with each other, a source of energy, circuit means controlled by said pair of contacts of said condition responsive switch for connecting said motor with said source of energy, holding circuit means for said motor independent of said pair of contacts of said condition responsive switch and controlled by said first named switch, a third switch, and means responsive to a condition normally established as a result of the movement of said valve to said second controlling position and operative upon the establishment of said condition to move said third switch to closed position, further electrically operated apparatus whose operation prior to the establishment of said last named condition is not desirable, and circuit means including and controlled by said first named switch and by said third switch for energizing said additional apparatus.

JOHN P. KRIECHBAUM. 35
